UNITED STATES PATENT OFFICE.

ROBERT FERRIS, OF YANKTON, SOUTH DAKOTA.

APPARATUS FOR DISPENSING ICE-CREAM OR OTHER MATERIAL IN PAPER CARTONS.

1,354,246.

Specification of Letters Patent. Patented Sept. 28, 1920.

Application filed April 8, 1920. Serial No. 372,177.

To all whom it may concern:

Be it known that I, ROBERT FERRIS, a citizen of the United States, residing at Yankton, in the county of Yankton and State of South Dakota, have invented certain new and useful Improvements in Apparatus for Dispensing Ice-Cream or other Material in Paper Cartons; and I do hereby declare the following to be a full, clear, and exact description of the invention, such as will enable others skilled in the art to which it appertains to make and use the same.

My invention has for its object to provide an improved apparatus for dispensing ice cream or other material in paper cartons formed at the time needed for use; and, to this end, my invention consists of the novel devices and combinations of devices hereinafter described and pointed out in the claims.

My invention is illustrated in the accompanying drawings, wherein like notations refer to like parts throughout the several views.

25 In said drawings:—

Figure 1 is a view in plan showing a sheet of paper of size suitable for the desired carton and the former in its initial position thereon with a portion thereof broken away and portions shown in section;

Fig. 2 is a vertical sectional view showing the former and the carton as these parts would appear when the carton has been formed on the former;

Fig. 3 is a view in vertical section showing the sectional holder with the carton therein as it would appear when the former has been withdrawn from the carton, leaving the carton in the holder in position for filling; and

Figs. 4, 5 and 6 are side elevations, with some portions broken away and some portions in section, showing the sections of the former separated from each other.

The paper employed for the cartons may be of any suitable kind, but is preferably parchment paper or paraffin paper and is cut into sheets 7, of the proper size for the carton desired. The numeral 8, as used in

Figs. 1 and 2, represents a cup-like former of nearly cylindrical but slightly tapering form, or with its lower end of little less diameter than its open top end or mouth, as best shown in Fig. 2; and which cup-like former has a central hole 8^a in its bottom

to admit air and prevent a vacuum, when the former is withdrawn from the carton in the holder, as will presently be noted.

This former 8 is applied to the sheet of paper 7, with its open upper end flush with one margin of the sheet and the sheet of paper is then rolled up onto the former by rolling the former and the paper together, and the lower projecting end portions of the paper are then folded together over the end of the former, and, if desired, may be pasted or otherwise secured together at that point, thereby forming the carton 7^a on the former 8, as shown in Fig. 2.

The numeral 9 represents an open ended split cylinder made out of suitable resilient material, such as tin, galvanized iron or other metal, and which is, therefore, contractible and expansible. The edges of the split cylinder may abut or overlap, with or without a lip, when the cylinder is in its contracted position.

This cylinder 9 is of the proper diameter to receive the former 8 with the carton 7^a thereon. The numeral 10 represents a cup-like base section with which said cylindrical or body section 9 is adapted to telescope at its lower end. The numeral 11 represents the top section of ring-like or open ended cylindrical form, adapted to telescope over the upper end of the body section 9 and cooperate with said cup-like base section 10, to hold said body section 9 in its contracted position.

When the said three parts 9, 10 and 11 are thus telescoped together, they constitute a suitable holder into which the carton 7^a can be placed by putting therein the former 8, small end downward, with the carton formed thereon, and then removing the former 8 from the carton 7^a, thereby leaving said carton standing with its upper end projecting outward and upward beyond the holder, as shown in Fig. 3. To insure this projecting end of the carton, the holder, made up of the telescoping sections 9, 10 and 11, is of less length than the former 8 and the carton 7^a formed thereon from the sheet 7, as shown in Fig. 2, as compared with Fig. 3 of the drawing.

When said former 8, with its carton 7^a thereon, as shown in Fig. 2, is placed in the holder, made up of the telescoping sections 9, 10 and 11, they will fill the holder and make up a comparatively tight joint be-

tween the holder and the former with the carton pinched between the two. The former 8 being of tapered form inserted with its small end downward, it can, however, be readily started outward by pulling upward on the projecting upper end of the same, and, as soon as it starts, air will be admitted through the hole 8^a of its bottom into the space between the former and the 10 carton, and thus prevent the forming of a partial vacuum, which would otherwise occur and interfere with the withdrawal of the former from the carton; and, because there is no air passage in the closed lower 15 end of the carton, the atmospheric pressure plus the friction between the carton and the holder will prevent the carton from being drawn outward with the former.

When the carton is thus left in the holder, 20 as shown in Fig. 3, its lower end will be resting on the inner surface of the bottom of the cup-like bottom section 10 of the holder and its upper end will be open, ready to receive the ice cream or other material, 25 and, when the carton is filled, the projecting upper end portions thereof may be folded inward over the top of the body of ice cream, as shown by dotted lines in Fig. 3, and be then pasted fast with a gummed 30 label, or be otherwise secured, if so desired.

Then, by removing the end sections 10 and 11 from the body section 9 of the holder, the latter will be thereby released from its contracted position and will automatically expand, and thereby drop off from the filled 35 carton, leaving the latter ready for delivery.

It must be obvious that this apparatus 40 enables an extremely cheap form of carton to be made and used, for holding the ice cream or other material, from almost any kind of available common wrapping paper, although parchment or paraffin paper is to be preferred. It will be understood, however, that the holder, herein illustrated and 45 described, would be serviceable, even if the cartons had been prepared in advance out of self-sustaining material and placed into the holder by hand, instead of with the usage of the former 8.

50 It will also be understood that the cup-like base section 10 might be sufficient to hold the longitudinally split body section 9 in its contracted position, without the co-operation of the top section 11; but it is desirable also 55 to employ the top section 11 to avoid breakage of the carton and to secure uniformity of diameter in the package of ice cream or other material.

It must also be understood that while the 60 former and the holder have both been illustrated as of cylindrical form in cross section, that this is simply the preferred form of these parts, and that they might be of polyhedral form in cross section of any number 65 of sides desired. All that is essential is that

the former and the holder should be of symmetrical form, so that the former and the carton formed thereon will fit the holder.

The practicability and utility of this apparatus have been demonstrated in the 70 actual commercial usage thereof for the purposes had in view.

What I claim is:—

1. An apparatus for dispensing ice cream or other materials in paper cartons formed 75 at the time needed for use, and which apparatus comprises a cup-shaped former on which the paper may be rolled and against the base of which its lower ends are adapted to be folded to produce a carton of cup-like 80 shape, and a carton holder comprising an expansible and contractible approximately cylindrical shell, and a non-expansible shell container which, when applied around said shell, limits the expansion of said shell to 85 such size that its interior is of but slightly greater diameter than the exterior of said former.

2. An apparatus for dispensing ice cream or other materials in paper cartons formed 90 at the time needed for use, and which apparatus comprises a cup-shaped former on which the paper may be rolled and against the base of which its lower ends are adapted to be folded to produce a carton of cup-like 95 shape, a carton holder comprising an expansible and contractible approximately cylindrical shell, and a non-expansible cup and collar, which cup and collar, when applied around said cylinder, limit the expansion of 100 the same to such size that its interior is of but slightly greater diameter than the exterior of said former.

3. An apparatus for dispensing ice cream or other material in paper cartons formed at 105 the time needed for use, and which apparatus comprises a cup-like former on which the paper is rolled and against the base of which its lower ends are folded together to get thereon a carton of cup-like shape, and a contractible and expansible carton holder, into which the carton is placed by putting said former therein with the carton thereon and then removing the former from the holder, and which holder is adapted, when 110 in its contracted position, to hold the carton while being filled, and adapted, when released, to expand automatically and drop away from the filled carton, substantially as described.

4. An apparatus for dispensing ice cream or other material in paper cartons formed at 115 the time needed for use, and which apparatus comprises a cup-like former, with a perforated base, on which former the paper is 120 rolled and against the base of which its lower ends are folded together to get thereon a carton of cup-like shape, and a contractible and expansible carton holder, into which the carton is placed by putting said former 125

therein with the carton thereon, and then removing the former from the holder, the perforation in the base of the former serving to admit air and prevent a partial vacuum between the former and the carton, substantially as and for the purposes set forth.

5. An apparatus for dispensing ice cream or other material in paper cartons formed at the time needed for use, and which apparatus 10 comprises a cup-like approximately cylindrical former, with a perforated base, on which the paper is rolled and against the base of which its lower ends are folded together to get thereon a carton of cup-like shape, and

a holder, of less length than said former, 15 composed of three telescoping cylindrical sections, the central or body member of which is made of resilient material and is longitudinally split so as to be contractible and expansible, the base member of which is 20 of cup-like form and telescopes with the lower end of the body section and the upper section of which is of open ring-like form and telescopes with the upper section of said body section for coöperation, substantially 25 as described and for the purposes set forth.

In testimony whereof I affix my signature.
ROBERT FERRIS.
